UNITED STATES PATENT OFFICE.

WILLIAM A. SCOTT, JR., AND WILLIAM WEHRMEYER, OF PITTSBURG,
PENNSYLVANIA.

CHECKREIN-HOLDER.

SPECIFICATION forming part of Letters Patent No. 423,636, dated March 18, 1890.

Application filed November 5, 1889. Serial No. 329,332. (Model.)

To all whom it may concern:

Be it known that we, WILLIAM A. SCOTT, Jr., a citizen of the United States, and WILLIAM WEHRMEYER, a subject of the Emperor of Germany, residing at Pittsburg, in the county of Allegheny and State of Pennsylvania, have invented or discovered a certain new and useful Improvement in Checkrein-Holders, of which improvement the following is a specification.

The invention described herein relates to certain improvements in checkrein-holders for horses, and has for its object such a construction of holder as will permit of a slackening of the checkrein and also a retightening of the same by the driver without leaving the buggy.

In general terms the invention consists in the construction and combination of mechanical devices or elements, all as more fully hereinafter described and claimed.

In the accompanying drawings, forming a part of this specification, Figure 1 is a perspective view showing our improved device attached to a harness on a horse. Fig. 2 is a horizontal sectional view of the rein-holder in normal position. Fig. 3 is a plan view of the same with the rein slack. Figs. 4 and 5 are detail views.

In the practice of our invention a plate or bracket 1 is attached to the saddle of a harness by a bolt 2, to which the plate is pivotally attached. A block 3 is secured at its inner end to this pivotal plate, and a similar block 4 is hinged to the block 3. These blocks 3 and 4 have axial holes formed therein, and in these holes are placed the spiral springs 5, having their inner ends secured in the bottoms of the holes, as shown in Fig. 2. The outer ends of the springs 5 are attached to the cylinders 6, which are preferably made hollow and of such external diameters as to fit freely within the springs 5. The checkrein 12 is made in two parts, and the ends of said parts are attached to the outer ends of the cylinders or shells. As shown in Figs. 2 and 3, the blocks 3 and 4 are so hinged together that when tension is applied to the checkrein they move toward each other in the direction of the horse's head; and in or-

der to prevent this movement except when desired a spring-catch 7 is fastened to one of the blocks, said catch being adapted when the blocks are in line with each other to engage a pin or hook 8 on the other block and hold the blocks in line. The springs 5 are closely wound and made of such a length that when free from tension they will lie wholly within the holes in the blocks and also pull the cylinders within their coils, as shown in Fig. 2.

A small cord or strap 9 is attached at one end to the spring-catch 7, and, passing through guide-loops on the back and hip straps, the other end, provided with a ring, hangs loosely on the horse's back, where it can be reached by the driver. By a pull on the cord 9 the catch is released from the pin 8 and the horse is permitted to drop his head, the blocks 3 and 4 turning forward into the position shown in Fig. 3. While the blocks are in this position the springs 5 can be drawn out, so as to allow the horse to drop his head as far as desired.

In order to return the device to normal position, the driving-reins are pulled slightly, causing the horse to throw his head up, thereby permitting the springs to retract into the blocks, carrying the shells or cylinders 6 with them. As soon as the springs have returned to normal position, as stated, the driver pulls the cord 10, one end of which lies loosely on the rump of the horse, and the opposite end is attached to the bridle or strap 11, whose ends are secured to the blocks 3 and 4 near their outer ends. By pulling on the cord 10 the blocks are turned rearwardly and into line with each other, so as to permit the spring-catch to engage the hook 8, locking the blocks in line with each other.

It will be readily understood that the cylinders or shells cannot be drawn out of the blocks by the horse except when the blocks are in the position shown in Fig. 3, and that therefore the springs cannot be in any way distorted.

When a buck-strap is used in lieu of the checkreins, the free end of said strap is connected by straps or chains to the cylinders 6 at their outer ends.

If desired, the cords or straps 9 and 10 may be made sufficiently long to extend back to the vehicle.

We claim herein as our invention—

- 5 1. In a checkrein-holder, the combination of two swinging blocks mounted on a plate adapted to be secured to the saddle of the harness, checkreins, and extensible connections uniting the blocks and checkreins, substantially as set forth.
- 10 2. In a checkrein-holder, the combination of two swinging blocks mounted on a plate adapted to be secured to the saddle of the harness and having holes formed therein, extensible springs having one of their ends secured within the holes in the blocks, and checkreins connected to the opposite ends, substantially as set forth.
- 15 3. In a checkrein-holder, the combination of two swinging blocks having axial holes formed therein, spiral springs having one of their ends secured within said holes, cylinders arranged within the springs and attached to the outer ends thereof, and checkreins connected to the cylinders, substantially as set forth.

4. In a checkrein-holder, the combination of two swinging blocks mounted on a plate adapted to be secured to the saddle of the harness, checkreins, extensible connections 30 uniting the checkreins and blocks, and a spring-catch for holding the blocks in line with each other, substantially as set forth.

5. In a checkrein-holder, the combination of two swinging blocks mounted on a plate 35 adapted to be secured to the saddle of the harness, checkreins, extensible connections uniting the checkreins and blocks, a bridle or strap for drawing the blocks into line with each other, a catch for holding them in such 40 position, and straps or cords connected to the bridle and catch and extending back over the horse, substantially as set forth.

In testimony whereof we have hereunto set our hands.

WILLIAM A. SCOTT, JR.
WILLIAM WEHRMEYER.
